UNITED STATES PATENT OFFICE

WILLIAM ROBERT LOWRY, OF INDIANAPOLIS, INDIANA

GLOVE-TURNING MACHINE

Application filed May 5, 1928. Serial No. 275,389.

This invention relates to a machine for turning gloves.

In the manufacture of gloves, it is the practice to sew the various parts of the glove 5 wrong side out and when the glove has been completely sewn it is turned so that the ragged edges of the seams will be on the inside. Heretofore, the practice has been to provide a foot propelled device wherein the operator 10 presses down on a foot lever for forcing the male members, or fingers, into their respective female members, or tubes, with the respective finger portions of the glove for turning the same. This requires a tremendous 15 physical exertion on the part of the operator, since there is considerable resistance to the turning of the gloves. The resistance to the turning and the exertion required increases with the heavier gloves so that under the most 20 favorable conditions an operator can only work part time upon the device, and there is danger of injurious effects resulting therefrom.

The object of this invention is to provide 25 a power driven machine for turning gloves, which may include mittens or the like, so that the operator need exert no physical force, but may control the power drive by relatively slight pressure upon a foot pedal. This the 30 operator can do while sitting down, as distinguished from the former operation which requires the operator to stand on one foot and exert full weight of the body in pressing down upon the operating foot lever.

This is accomplished by means of a compressed air cylinder and plunger connected 35 to the movable member of the turning device, and suitably controlled air passages for permitting the turning device to be forced into 40 and out of glove turning position by the compressed air in such manner that the operation may be easily regulated and controlled by the operator. In this respect it is essential that the turning device be sensitive to control in 45 order that there will be no damage to gloves that are not properly positioned for turning or which may be defective in some respects.

The full nature of the invention will be understood from the accompanying drawings 50 and the following description and claims:

Figure 1 is a side elevation of the machine. Fig. 2 is a front elevation thereof. Fig. 3 is an enlarged section through the glove turning device showing a glove being turned.

In the drawings there is shown an operating table 10 upon which there is secured an upright standard 11 mounted on the base 12. The base 12 supports the female member 13 of the glove turning device, which comprises a plurality of upwardly extending tubular 55 projections 14. Reciprocably mounted in the upper end of the standard 11 there is a plunger rod 15 having the male member 16 of the glove turning device secured to the lower end thereof and including a plurality of prongs 17 adapted to extend into the corresponding tubular projections 14.

Fixedly mounted upon the upper end of the standard there is a compressed air cylinder 70 having a piston or plunger 19 reciprocable therein and secured to the rod 15. Opposite ends of the cylinder 18 are connected with the compressed air lines 20 and 21 which are in communication with the main compressed air line 22 leading from a source of compressed air not shown herein. The main air line is controlled by the valve 23, and the branch lines 20 and 21 are controlled by the valves 24 and 25. The valves 24 and 25 have connected therewith the levers 26 and 27 which 75 are connected by the link 28. Pivotedly connected with the link 28 there is an operating lever 29 fulcrumed at 30 on the support 31 and having its opposite end connected with the rod 32 extending downwardly through 80 the table 10. The lower end of the rod 32 is adjustably secured to the control pedal 33 intermediate its ends, one end of said pedal being pivoted to the fixed support 34 and the other end having a foot pedal 35.

In operation, a glove 36 is mounted over the female member 13 in the form in which the seams are sewn, i. e., with the wrong side out. The male member is raised, as illustrated in Fig. 1. In this position, the valve 24 is opened, as well as the valve 23, while the valve 25 is closed. Thus, the pressure exerted by the compressed air is directed upwardly against the bottom side of the plunger 19, holding the male member in 95 100

raised position. With the glove so placed, the operator presses down upon the foot pedal 33, which, through the rod 32 and lever 29, raises the link 28 which carries the levers 26 and 27 to a position opening the valve 25 and closing the valve 24. Thereupon the compressed air is directed through the branch pipe 21 into the top of the cylinder and against the top surface of the plunger 19 so as to force the male member downwardly into the position illustrated in Fig. 3 and thereby engaging the fingers of the glove and forcing them into the tubes 14 so that they are reversed. This permits the operator to pull the body of the glove upwardly whereupon the body and fingers are turned as desired.

The valves 24 and 25 are provided with suitable exhaust ports 37 of the usual character for permitting the exhaust of the air from the cylinder when the valve is closed.

The male member 16 is normally raised and held in position by reason of the valve 25 being in closed position due to the tension 38 connecting the outer end of the lever 29 with the main supply pipe 22. The members are selectively operated by the touch or pressure exerted thereby upon the foot lever 33 so that the timing of the operation may be completely controlled by the operator, as well as the extent of the operation. Thus, if the operator finds a defect in the glove, or if for any other reason it is undesirable for the machine to operate through a complete cycle, the release of the pressure on the pedal will immediately arrest the downward movement of the male member and cause it to return to upper position.

For further steadyng and quieting the reciprocating movement of the male member 16 and rod 15, said rod is provided with a clamp 39 having a guide rod 40 extending upwardly therefrom, adapted to slide in the projections 41 and 42 extending laterally from the upper part of the upright standard 11.

From the foregoing it will be noted that although the power due to the compressed air is ample to turn a glove of any size or thickness of material, it is very sensitive to the control of the operator. In use, the physical exertion required for the operator is negligible.

The invention claimed is:

1. A machine for turning gloves or the like, including a female member upon which the glove is adapted to be positioned, a male member adapted to be forced therein for turning the glove, a compressed air cylinder fixedly mounted on said machine, a plunger reciprocably mounted therein and connected with one of said members, branch conduits leading from a source of compressed air and communicating with the ends of said cylinder, valves for controlling the passage of compressed air therethrough, and means for actuating said valves for controlling the

action of the compressed air on said plunger for forcing said members in and out of operative position.

2. A machine for turning gloves or the like, including a female member upon which the glove is adapted to be positioned, a male member adapted to be forced therein for turning the glove, a compressed air cylinder fixedly mounted on said machine, a plunger reciprocably mounted therein and connected with one of said members, branch conduits leading from a source of compressed air and communicating with the ends of said cylinder, valves for controlling the passage of compressed air therethrough, and a foot operated pedal operatively connected with said valves for controlling the action of the compressed air on said plunger, whereby said members may be selectively operated to bring them in and out of engagement.

3. A machine for turning gloves or the like, including a female member having a plurality of upwardly extending tubular projections over which the glove to be turned is adapted to be positioned, a male member suspended above said female member and provided with a plurality of fingers adapted to extend into said tubes for turning the glove therein, an upright support in which said male member is slidably mounted, a compressed air cylinder mounted on said support, a plunger reciprocable therein and connected with said male member, branch conduits leading to opposite ends of said cylinder from a source of compressed air supply, a valve in each of said conduits, linkage connecting said valves, whereby one valve will be opened when the other is closed, and a foot operated pedal connected with said linkage for controlling said valves and causing said male member to be selectively operated for engagement and disengagement with said female member.

In witness whereof, I have hereunto affixed my signature.

WILLIAM ROBERT LOWRY.
